UNITED STATES PATENT OFFICE

2,051,550

COTTON GIN

William H. Dodson, Torreon, Mexico, assignor to
 The Murray Company, Dallas, Tex., a corpora-
 tion of Texas

Application September 27, 1934, Serial No. 745,704

3 Claims. (Cl. 19—59)

This invention relates to new and useful im-
 provements in cotton gins.

One object of the invention is to provide an
 improved cotton gin of the pneumatic type in-
 volving certain features making for a more effi-
 cient, more accessible, and less expensive ginn-
 ing structure, requiring less power to operate
 and producing a smoother and more uniform
 deposit of the lint in the bale, as well as giving
 10 the finished cotton a better grade and a higher
 value.

A particular object of the invention is to pro-
 vide a new arrangement of the lint conductor in
 the gin stand, whereby the tortuous or upward-
 15 curve of the present lint conductor is elimi-
 nated and a straight flaring conductor extend-
 ing substantially tangentially to the upright
 portion of the conductor is substituted for the
 curved conductor.

20 A further object of the invention is to pro-
 vide a flaring connection between the flaring
 end of the lint conductor and the lint flue, so
 that the conductor and the connection coacting
 25 tend to induce the internal frictional distance
 to the discharge of the lint, whereby less air
 velocity or pressure is required, thus permitting
 the use of smaller fans and a reduction in
 the power required to operate, as well as tend-
 ing to reduce back pressure.

30 An important object of the invention is to so
 arrange the lint conductor in the gin stand that
 the line flue and the transition connecting the
 conductor and the flue may be located below
 35 the floor on which the gin stand is mounted,
 whereby the floor space behind the gin is unob-
 structed and enabling the operator to have free
 access to the back of the gin stand for clean-
 ing and other purposes without climbing over
 the usual lint flue and other obstructions.

40 A construction designed to carry out the
 invention will be hereinafter described, together
 with other features of the invention.

The invention will be more readily understood
 45 from a reading of the following specification and
 by reference to the accompanying drawing, in
 which an example of the invention is shown,
 and wherein:

Figure 1 is a transverse vertical sectional view
 50 showing a portion of the pneumatic gin stand
 now in common use and the lint flue connected
 therewith, and

Figure 2 is a transverse vertical sectional view
 55 showing a portion of a gin stand having a lint
 passage connected with the lint flue, arranged

under the floor and constructed in accordance
 with the invention.

In the drawing the numeral 10 designates an
 ordinary pneumatic gin stand of a construction
 now in common use, as shown in Figure 1. The 5
 stand is provided with an air flue 11 for sup-
 plying air under pressure and this flue is con-
 nected with an air chamber 12 from which the
 usual air duct 13 curves upwardly to the nozzle
 14. The saws 15 project into the upper end of 10
 the lint conductor or duct 16 so that the air
 discharged from the nozzle will blow the lint off
 the teeth down into the duct. This duct is
 given a slight flare downwardly and is curved
 around and under the duct 13 and the flue 11. 15
 The discharge portion of the duct curves up-
 wardly, as is shown in Figure 1, and is con-
 nected by means of a transition 17 with the
 lint flue 18.

It will be observed that the lint duct 16 curv-
 ing upwardly requires sufficient air velocity to
 lift the lint after it has passed the bottom or
 dip X in said duct. In order to keep the lint
 20 in suspension, it is necessary to drag it along
 the top wall Y of the duct, and this increases
 the resistance. Further, the lint must be lifted
 through the transition 17 to the flue 18. It
 often becomes necessary for the operator to
 25 get to the back of the gin stand and he is com-
 pelled to climb over the flue 18 and stand at one
 side of the transition 17.

The improved structure is shown in Figure 2
 and resides in straightening and lowering the
 lower portion of the duct 16, whereby a recti-
 linear flaring discharge conductor 19 extends 35
 downwardly and tangentially from the upright
 portion of the duct 16. This eliminates a large
 portion of the curvature, as well as the upward
 direction of the curvature and gives the lint the
 advantage of gravity in its downward passage. 40
 The flare of the conductor 19 permits the lint
 to remain in suspension without undue resist-
 ance from frictional contact with the walls of
 said conductor. The conductor extends below
 45 the floor A, on which the gin stand is mounted.
 The discharge end of the conductor is connected
 with a transition 20, which is also mounted under
 the floor. This transition is connected with a
 cylindrical spout 21 of a lint flue 23.

It will be noted that the transition, the spout 50
 and the lint flue are all below the floor and that
 both the transition and the spout are given a
 downward inclination so that the lint starting
 down the conductor 19 has a straight downward
 55 passage of constantly increasing area until it

reaches the large spout 21. This certainly makes for a more efficient operation and reduces the power necessary to operate. The lint is less likely to become matted and a better grade is produced. The clearing of the floor space in back of the gin is an important feature. A comparison of Figs. 1 and 2 will demonstrate how the lint flue obstructs the back of the gin and how its disposition under the floor removes all obstruction to the back of the gin and gives ready access thereto.

What I claim and desire to secure by Letters Patent is:

1. A cotton gin including, in combination with the floor of a gin house, a gin stand mounted on the floor, a lint duct extending transversely and downwardly in the gin stand to and through the floor, said duct having a continuous fall, whereby the frictional resistance to the downwardly moving cotton is reduced, a flaring transition connected to and extending from the lower end of the lint duct below said floor and relatively to the rear of said gin stand, and a lint flue connected to the outer discharge end of the transition and extending at an angle thereto below the floor, whereby the floor immediately in rear of the gin stand is unobstructed, the lint from the gin stand being conducted in a continuous downward direction, whereby frictional resistance is reduced and the air suction load is lowered.

2. A cotton gin including, in combination with the floor of a gin house, a pneumatic gin stand adapted to form one of a battery of gin stands

mounted on the floor, a lint duct curved downwardly and transversely in the gin stand to and through the floor to the rear of said gin stand, said duct having a continuous fall, whereby the frictional resistance to the downwardly moving cotton is reduced, a transition immediately below the floor extending from the lower end of the lint duct and to the rear end of said gin stand, and a longitudinal lint flue adapted to be connected to a battery of gin stands and connected to the outer discharge end of the transition and extending at an angle thereto below the floor, whereby the floor immediately in rear of the gin stand is unobstructed, the lint from the gin stand being conducted in a continuous downward direction, whereby frictional resistance is reduced and the air suction load is lowered.

3. A cotton gin including, in combination with the floor of a gin house, a gin stand mounted on the floor of the gin house, a lint duct extending downwardly of the gin stand to and through the floor, a flue connection extending from the discharge end of the lint duct, and a longitudinal lint flue located beneath the floor in rear of the gin stand and connected with the duct by said connection, whereby the floor in rear of the gin stand is unobstructed, the lint from the gin stand being conducted downwardly to the lint flue below the said gin stand and along said flue, whereby the air and lint from above are discharged into the lint flue to slide the lint in bulk without cyclonic action.

WILLIAM H. DODSON.
